DOOR AND WINDOW STRUCTURE

Frank D. Unterberger, Murrysville, Pa., assignor
to Steve Kinchem, Murrysville, Pa.

Application May 7, 1947, Serial No. 746,552

4 Claims. (Cl. 160—40)

1

This invention relates to doors, and more particularly to doors of the all-weather type for use with the usual doors used in dwellings, although certain features of the invention are suitable for use in bathroom doors and other doors.

One object of my invention is to provide a door of the type referred to wherein panels that comprise fly screen, glass, and sheet metal can readily be substituted for one another, to suit seasonal conditions, simply by the use of locking strips or bars that can readily be slid into and out of panel-retaining position.

Another object of my invention is to provide a door of the type referred to which is of lighter weight than doors of conventional form and which is, nevertheless, of adequate strength and durability.

Some of the forms which my invention may take are shown in the accompanying drawings, wherein Figure 1 is an outer face view of a door; Fig. 2 is an enlarged view taken on any of the lines II—II of Fig. 1; Fig. 3 is an enlarged view taken on the line III—III of Fig. 1; Figs. 4 and 5 are edge and face views, respectively, of a form of holding and sealing strip that is movable to cover and uncover an air-circulation opening in the door; Fig. 6 is a view taken on the line VI—VI of Fig. 10; Fig. 7 is an enlarged view taken on the line VII—VII of Fig. 1; Fig. 8 shows a modification of the rail of Fig. 7; Fig. 9 shows still another modification thereof; Fig. 10 is an enlarged face view of one of the corners of the panel frame that holds a fly screen; Fig. 11 is a view showing the inner face of the door of Fig. 1; Fig. 12 is an enlarged view showing a modification of the lower portion of the door of Fig. 1 and the relation of the outer door to the inner door, and Fig. 13 is an enlarged sectional view showing one of the breather openings in the uppermost rail of Fig. 1.

The structure comprises stiles 15 having rails 16 and 17 welded thereto in mitered relation at the upper and lower ends of the stiles. Intermediate rails 19 and 20 (Figs. 3 and 7) are welded at their ends to the stiles 15. These parts are preferably made of light weight metal such as aluminum.

Each of the stiles and rails 15—16—17 has a flange 21 to provide an angular seat for a panel frame such as the frame 22 of Figs. 1, 2 and 10. The screen frame 22 is formed of rectangularly-arranged bars 22 welded together and having grooves to receive clamping rods 23 that will hold a wire cloth or screen 24 at its four edges.

The corners of the frame 22 are reinforced by angles 18, as shown more clearly in Figs. 6 and 55

10, such bars snugly fitting within the angle at each corner and being welded in place. This screen frame is placed against the flanges 21, from the inner side of the door, the lower edge of the screen frame being inserted into the upwardly exposed channel of the rail 19 as shown more clearly in Fig. 3. Locking strips 25 are then inserted in grooves such as 16a (Fig. 13) formed in the stiles 15 and the rail 16, as shown more clearly in Figs. 2 and 11. These locking strips have snug fit with their grooves so that they will be frictionally held in place, and they have flanges 25a to facilitate driving them into place and for removing them.

15 An intermediate panel 26 of glass has a rectangular protecting frame 28 of channel form in cross section encompassing its edges. The frame 28 is preferably of rubber-like material. The upper edge of this panel is inserted into the lower channel of the rail 19 (Fig. 3). Its vertical edges are held in place against the flanges 21 of the stiles 15, by locking strips such as the strips 25 that extend into the vertical grooves 16a (Figs. 2 and 13) of the stiles 15. The lower edge of the glass, with its packing 28 fits within a channel 29 (Fig. 7) that is supported on the rail 20 by a locking strip 31, the locking strips 25 and 21 being, of course, removable to permit placing a panel of wire or thin sheet metal where no glazing is desired.

The lowermost panel frame 32 of the door may suitably be of sheet metal held in a frame formed of rectangularly-arranged bars 33 that may suitably be of substantially the same form as the screen frame bars 22. The frame formed by the member 33 is releasably held at its upper edge in place by a locking bar 34 (Fig. 7) which snugly fits into a groove in the rail 20. The vertical and bottom edges of the frame are held in place against the stiles and the bottom rail 17 by locking bars such as 25.

45 As explained above, panel substitutions may readily be made so that glass, screen or flat sheets can be used in any or all of the various panel areas. In Fig. 8 is shown a modified form of intermediate rail 37 which is especially suitable where a plurality of sheet metal panels 38 are desired, or where a combination of sheet metal and screen panels are desired. The frames 39 for these panels will be held in place by locking bars 41, at their horizontal edges, while their vertical edges will be held in place against the flanges 21 of the stiles by locking bars 25. It will be seen that the rail 20 of Fig. 7 can also be utilized to

hold a screen frame or a sheet metal panel frame instead of the glass.

In Fig. 9 is shown a modification of the rail of Fig. 8. In this arrangement, a rail 42 has a closure plate 43 held in place by a screw 44. The utility of this arrangement resides in the fact that the welds which joint the ends of the rail to the stiles 15 can be made at the inner surfaces of the rail, therefore having them in concealed locations. After completion of the welds, the cover 10 plate 43 will be attached.

Referring now to Fig. 12, I show an air-circulation opening for the door frame, whereby, in cold weather, there may be some circulation of air between this door and the regulation door indicated at 45, when this door is being used as a storm door, to thereby avoid condensation of moisture or sweating on the opposed faces of the doors. In this arrangement, a rail 46 is substituted for the rail 20 of Figs. 1 and 7 and the lower panel frame 33 is spaced below the rail 46 to provide a slit 47 through which outside air may circulate to somewhat equalize temperatures at the inner and outer faces of the storm door. The frame 33 will rest upon and be supported by the bottom rail 17 and will be held in place by the locking strips 25. A strip 48 is slidably supported on the upper bar of the frame 33 and is frictionally held in vertically-adjusted positions by a headed pin or rivet 49, the strip being provided with elongated holes 50 (Figs. 5 and 12). The ends of the strip 48 are slidable in the vertical grooves of the stiles 15.

Referring now to Figs. 1, 11 and 13, I show breather openings through the door frame to permit of movement of air through the door, as when there is no screen panel in the door. These breather openings allow such movement of air that there will be no pressure or suctional resistance to movement of one door when the other door is in its closed position.

To this end, openings are provided through the outer walls of the cross bar 16, the openings having eyelets 52 to give them a finished appearance, and having screens 53. At the opposite face of the door, holes 54 are provided through the inner wall of the rail 17. The stiles 15 and the rails 16 and 17 being hollow, there will be movement of air through the stiles and the holes 52 and 54 when pressure or suction is created between the inner and outer door through relative movements of the doors.

I claim as my invention:

1. A door comprising a frame having side stiles of hollow sheet-metal construction, rails connecting the stiles adjacent to their upper and lower ends, flanges on the inner edges of the stiles and the rails, adjacent to one face of the frame and extending toward the panel area, to thereby form angular seating surfaces of elongated form, there being grooves formed in the inner edges of the stiles and the rails, adjacent to the other face of the frame and parallel to the

said flanges, and locking bars insertible into the grooves but partly protruding therefrom, to retain a panel-like element in position against the flanges, there being breathing openings through the outer and inner walls of the frame and having communication with one another, through the hollow spaces in the frame.

2. A door comprising a frame having side stiles of hollow sheet-metal construction, rails connecting the stiles adjacent to their upper and lower ends, flanges on the inner edges of the stiles and the rails, adjacent to one face of the frame and extending toward the panel area, to thereby form angular seating surfaces of elongated form, 15 there being grooves formed in the inner edges of the stiles and the rails, adjacent to the other face of the frame and parallel to the said flanges, and locking bars insertible into the grooves but partly protruding therefrom, to retain a panel-like element in position against the flanges, there being breathing openings through the outer and inner walls of the frame and having communication with one another, through the hollow spaces in the frame, the outer opening being located adjacent to one end of the frame and the inner openings located adjacent to its other end.

3. A door comprising a frame having side stiles, rails connecting the stiles adjacent to their upper and lower ends, an intermediate rail connecting the stiles, panel frames secured to the stiles and the upper and lower rails, the upper edge of the lowermost panel having one of its horizontal edges spaced from one of the rails, and a sealing strip carried by the door and slidable thereon to close and open the said space.

4. A door comprising a frame having side stiles, rails connecting the stiles adjacent to their upper and lower ends, an intermediate rail connecting the stiles, panel frames secured to the stiles and the upper and lower rails, the upper edge of the lowermost panel having one of its horizontal edges spaced from one of the rails, and a sealing strip carried by the door and slidable thereon to close and open the said space, the door frame 30 being hollow and having breathing openings therein that open to the inner and outer faces of the frame, the outer openings being adjacent to one end of the door and the inner openings adjacent to its other end.

FRANK D. UNTERBERGER.
